CLAIM

The ornamental design for a display screen with a graphical user interface for automobile repair estimation and recommendation, as shown and described.

DESCRIPTION

(62) Division of application No. 29/518,133, filed on Feb. 20, 2015, now Pat. No. Des. 775,142.

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. The FIGURE is a front view of a display screen with a graphical user interface for displaying automobile repair information including repair center recommendations and availability.

(51) **LOC (10) Cl.** **14-04**

The outermost broken line showing the display screen with graphical user interface is included for the purpose of illustrating the article and forms no part of the claimed design. The broken lines within the display screen represent elements of the graphical user interface, text, and symbols that form no part of the claimed design.
